DESIGN FOR A SUIT

Shirley Karson, New York, N. Y.

Application December 1, 1943, Serial No. 111,850

Term of patent 3½ years

To all whom it may concern:

Be it known that I, Shirley Karson, a citizen of the United States of America, residing in New York, county of New York, and State of New York, have invented a new, original, and ornamental Design for a Suit, of which the following is a specification, reference being had to the accompanying drawing, forming part thereof,

Figure 1 is a front view of a suit showing my new design, one of the coat corners being raised to show the skirt trim.

Fig. 2 is a rear view thereof.

I claim:

The ornamental design for a suit, substantially as shown.

SHIRLEY KARSON.
